American Stove Company, St. Louis, Mo., a
corporation of New Jersey

Application November 18, 1939, Serial No. 305,199

7 Claims. (Cl. 158—115)

The present invention pertains to an automatic fuel control for the burner or burners of a gaseous fuel heated device, particularly a gas cooking range, and has as its primary object the provision of such a valve in combination with means for automatically igniting the heating burner.

Another object of the invention is the provision of an automatic ignition means for a gaseous fuel burner which by reason of a safety fuel valve provides a device which is fool-proof in operation.

Another and still further object of the invention is the provision of a device having the foregoing attributes which is cheap and simple of manufacture, highly efficient in operation and readily, easily and comparatively cheaply applicable to a gas cooking range.

Other specific objects, novel features of construction and improved results which are inherent in the structure which has been conceived to obtain the desired results will appear in more particular in the following detailed description when read in the light of the accompanying drawings which illustrate one form in which the inventive concept may be embodied.

In the drawings:

Fig. 1 is a fragmentary view in front elevation of a gas cooking range having applied thereto the present invention.

Fig. 2 is a fragmentary top plan view illustrating the manner of application and association of the present improved invention to a gaseous fuel burner.

Fig. 3 is a top plan view of the improved device, the improved control valve being illustrated in horizontal section.

Fig. 4 is a longitudinal vertical sectional view through the constant burning pilot light and thermal responsive member, the safety control valve being shown in side elevation.

Having reference to Figure 1 of the drawings and describing the invention in broad terms rather than resorting to specific description, A designates a gas cooking range which may be of any desired and conventional type or construction and which is provided with an oven chamber lying behind a door 1 and having therein any conventional type of gas burner B. A main gas manifold or conduit 2 has suitable connection with any source of fuel supply (not shown) and serves as the feeding means for fuel delivered to the oven burner B, a constant burning pilot burner or light C, and a booster burner D. Fuel for the oven burner is primarily

conveyed from the main manifold 2 through any suitable and conventional heat regulator 3, the setting of which is under control of a setting handle 4, and from said regulator through a fuel conduit 5 the discharge end of which (see Figure 3 of the drawings) is in communication with the tapped opening 6 of the automatic fuel control valve housing E. Fuel is constantly delivered from the main fuel manifold 2 through a conduit 7 the discharge end 8 of which, see Figure 4 of the drawings, is suitably connected to the constant burning pilot light C. The volume of fuel permitted to flow through the conduit 7 is controllable by a suitable valve 9. Fuel for the booster burner flows to said burner through a conduit 10 which has its supply end connected to a fitting 11 which interconnects the heat regulator with the main fuel supply pipe 2. The connection of the conduit 10 is at a point in front of the heat regulator and hence the flow of gas therein is in no wise under the control of the regulator. The flow of fuel to both the conduit 10 and the heat regulator is under the control of a manually operable valve 12 interposed in the line which connects the heat regulator 3 and the conduit 10 with the main supply manifold 2. The discharge end 13 of the conduit 10 is connected to a valve fitting 14 which has communication past a needle valve 15 with the hollow interior 16 of the booster burner D.

Having described the invention generally and broadly, specific description of the parts will now be given.

The safety valve housing E has an inlet chamber 18 which receives fuel through an inlet 22 and this chamber is in communication with an outlet chamber 17 past the valve 19 which is normally urged to a closed position against its seat 20 through pressure exerted by a coil spring 21. The outlet chamber 17 is provided with an internally tapped outlet opening 6 to which is connected, see Figure 2 of the drawings, a fitting 23 provided with a fuel outlet nozzle or jet 24 which discharges fuel into the bell shaped inlet end 25 of the oven burner manifold 26.

The safety fuel control valve 19 is mounted on one end of a pin 27 and held in engagement therewith by the pressure of the coil spring 21. This pin is reciprocable within a suitable bushing 28 which serves as a guide and the outer end 29 of the pin is in engagement with one end of a sheet metal lever F the opposite end of which is penetrated by a pin 30 carried on the inner end of an adjusting screw 31 against the inner end of which the lever abuts. The pin 30

serves as a means to retain the lever in engagement with the end of the adjusting screw which serves as a pivotal point for the lever and this pivotal point is adjustable by adjusting the screw 31 in and out by the application of a screw driver or other suitable tool to its outer curved end 32. The adjusting screw 31 is locked in its adjusted position by a lock nut 33.

The safety valve housing E is provided with a web or flange 34 which lies between the lever F and the main oven burner B as well as the pilot light and booster burner, as will be clearly apparent by reference to Figure 2 of the drawings, and this web is provided with an opening 35 for the passage of the end 36 of a thermal member G which is illustrated as being tubular in form. It is to be understood however that a rod could be substituted for a tube but a tube is found to be more desirable in that it contains less mass and is therefore more rapidly responsive to heat and will tend to cool more rapidly than a rod. In other words, the tube gives a quick thermal response which results in a fast operation of the fuel valve 19 as will more clearly hereinafter appear.

The booster burner D is illustrated as being formed integrally with the fuel control valve housing E but integral formation is not the essence of the present invention. The booster burner D is of narrow elongated form and extends outwardly at right angles from the valve housing and in its upper face is provided with a plurality of burner orifices 37 arranged in spaced aligned relationship and having communication with the hollow interior fuel conduit like portion 16 of the burner. At its outer end the booster burner housing is slotted to provide a burner orifice 38 in respect to which the upturned outlet and flame burning end 39 of the constant burning pilot light C is closely positioned. Secondary air is admitted to the fuel within the hollow booster burner through a suitable air inlet port 40 which is positioned closely adjacent the fuel inlet orifice 41 which in combination with the hereinbefore mentioned needle valve 15 serves to meter the fuel delivery to the booster burner. Secondary air is admitted to the constant burning pilot light C through an air inlet port 42.

At its outer end the booster burner is provided with an extension H which we term a carrier and which has its outer end turned upwardly to form a vertically extending leg 43 provided with an opening which threadedly receives a plug 44.

The thermal element G at its inner end 36 is provided with a pin 45 which passes through a suitable opening in the lever F which is closely adjacent to the hereinbefore mentioned pin 30 but lies between that pin and the opposite end of the lever which engages the valve operating pin 28. The inner end 36 of the thermal element actually engages the lever and extends from the lever all the way to and has its outer end 46 supported within the vertical leg 43 of the carrier H. The burner orifices 37 in the upper face of the booster burner D are in a line immediately below the thermal element so that the flames 47 burned at the orifices play on the under side and around the thermal tube. The disposition of the parts is also such that the flame 48 burned by the constant burning pilot light also plays upon the under side and licks around the thermal element or tube, as clearly appears in Figure 4 of the drawings.

The screw plug 44 serves as a convenient

means for assembling the thermal member G. Removal of the plug permits ready and easy removal and replacement of thermal members in the device.

To protect the booster burner flames 47 from draft or possible interference from the closely adjacent flames of the main burner a shield 48 is secured as at 49 to one side of the booster burner and extends for a considerable distance between the booster burner and the main burner B.

By reference to Figure 2 of the drawings it will be seen that the main burner is of the cross-fire type having two parallel lines of burner orifices 50 and 51 from which are intended to burn oppositely extending flames. At a point closely adjacent the pilot flame 48 a row of ignition burner orifices 52 extend to provide a chain lighter which will assure ignition, by the constant burning pilot light, of fuel issuing from the main burner ports of the main burner. The carrier H as well as the plug 44 are composed of what might be well termed a "negative" material by which is meant that these parts have an extremely low coefficient of heat expansion as compared with the high coefficient of expansion of the thermal member G. The plug 44 obviously constitutes an abutment against or from which the thermal member expands to exert the required pressure on the valve operating lever F.

By reason of the fact that the full expansion of the thermal element and the consequent full opening of the valve is responsive entirely to the heat generated by the booster burner the pilot flame at the pilot light burner may be adjusted by the valve 9 to be extremely small with a consequent minimum cost of continuous operation of the pilot burner. The flame is however made sufficient so that the burner generates sufficient heat to cause an initial slight opening of the safety control valve 19 and is sufficient at all times to ignite the booster burner and the main burner when fuel is supplied to them.

The size of the flame burned at the booster burner is readily adjustable by the needle valve 15 and inasmuch as the fuel conduit 16 for the booster burner receives fuel from a point in front of the heat regulator 3 the size of the flame burned at the booster burner is not affected by the particular setting of the heat regulator. Consequently the position of the safety control valve 19 does not change irrespective of the action of the oven heat regulator in increasing or decreasing the fuel supply and the size of the flame burned at the main burner. It will be seen from the foregoing that when neither the booster or main burners are lighted the oven is not heated but is relatively cold and the valve 19 is slightly open, and when the manually operated valve 12 is opened gas flows at once to the booster burner G which is lighted by said pilot burner without further opening the main burner valve 19. The large booster burner being adjacent the single thermal member as shown the latter is quickly heated and expanded and the thermal member quickly fully opens the valve 19 without the necessity of waiting until the oven is sufficiently heated to expand the single thermal member for that purpose.

The sheet metal lever F is not within the safety control valve housing E but is disposed in the space 53 which separates the web 34 from this housing. The web 34 serves as a shield to protect the lever from any accidental displacement. The construction also makes it possible to vis-

ually observe the setting of the device. The device must be set so that the valve 19 is operated at the proper time and as to whether or not the device is properly set can be readily ascertained by observing the clearance between the end 54 of the lever and the valve operating pin 29. Adjustment is conveniently available through the pin 31 after the lock nut 33 has been loosened. The preferable and best adjustment has been found to be one which will enable the insertion between the end of the lever and the pin 29 of a spacer having a thickness from 0.020 to 0.030 without causing the valve 19 to open. The less the clearance between the lever and the end of the pin the more rapid will be the opening of the valve but the closing time thereof will be slower.

In operation the ignition of the main burner is automatic after the manual control valve 12 has been opened. The opening of this valve permits fuel to flow to the booster burner which is ignited automatically by the constant burning pilot light. Simultaneously fuel will flow through the oven heat regulator and into the inlet or receiving chamber 18 of the automatic valve housing. The constant burning pilot light has maintained the thermal element in a sufficient degree of expansion as to have caused the valve 19 to be slightly open so that the fuel from the chamber 18 can flow into the outlet chamber 17 and through the conduit or fitting 23 into the intake manifold of the main burner and from there to the burner orifices of the main burner where it will be ignited by the constant burning pilot light. Within a few moments the increased heat directed against the thermal member by the flames burned at the booster burner will cause further expansion of that member which expansion will cause the valve 19 to be fully opened so that a maximum supply of fuel and a maximum flame can be obtained at the main burner. Thereafter and until the manual valve 12 is closed the operation of the main burner is under the automatic control of the heat regulator 3.

It will be seen that the manually operated valve 12 can be opened with perfect safety because the valve 19 will be closed and no fuel can reach the main or auxiliary burners unless the pilot light burner is ignited. If the pilot light burner is ignited the passage of fuel to the main and auxiliary or booster burners can be permitted with safety because the flame of the pilot burner stands ready to ignite said fuel as soon as it escapes through the burner orifices of the main and booster burners.

It will be further seen that the present device provides one which can be operated at an extremely low cost inasmuch as the constant fuel consumption of the constantly burning pilot light will be extremely small due to the fact that the flame burned at this burner can be maintained very low due to the cooperative booster action exerted through the thermal member upon the safety valve by the booster or auxiliary burner.

It will be further seen and readily understood by those familiar with this art that the present device is unusually simple of construction and as a consequence the likelihood of failure of operation is materially reduced and that the cost of manufacture and assembly is also materially reduced over those devices now known and made for the purpose of providing automatic ignition and fuel control for burners.

We claim:

1. In a gas range the combination of a com-

bustion chamber having a main burner, a fuel manifold connected with said main burner, a combined safety and controlling gas valve housing, a combined safety and main gas controlling valve in said housing, a thermal member located inside of said chamber and operatively connected with said valve, a fuel conduit outside of said chamber and connected with said housing and having a manually operated valve outside of said chamber for controlling the flow of fuel to said valve housing, a pilot light within said chamber and located under said thermal member for slightly expanding said thermal member when burning to partially open said combined main gas controlling and safety valve, and a booster burner located wholly within said chamber and under said thermal member within said chamber to quickly furnish additional expanding heat directly thereto to cause said main controlling valve to fully open and feed a full supply of gas to said main burner for the purpose described, and a fuel conduit connecting said pilot burner with said manifold extending outside of and independent of said combined safety and main gas control valve housing, the last said conduit having a manual control for said fuel conduit located outside of said chamber, said parts operating as and for the purpose described.

2. A range constructed as defined in claim 1, wherein said thermal member has a booster burner extension and an elongated booster burner under said thermal extension and a fuel feeding conduit between said booster burner and the manual operated valve outside of said chamber, whereby said extension of said thermal member and said booster burner will quickly fully expand under the booster burner heat and quickly open said main fuel controlling valve without waiting for the combustion chamber to become sufficiently hot to cause said expansion of said thermal member.

3. A gas appliance of the type disclosed, comprising an oven, a main burner, a manifold, a conduit connecting the main burner with said manifold, a heat regulator controlling the flow of fuel to said main burner, a pilot burner adjacent said main burner, a pilot conduit attached to said manifold independently of said main burner conduit, a combined main gas and safety valve housing having a single valve seat therein, a single one-way acting safety valve co-acting with said single valve seat within said housing and acting to control the gas for the main burner, a thermal member in said oven and operatively connected with said single one-way acting safety valve, a booster burner directly heating said thermal member while the pilot is burning and also causing the quick feeding of the gas to the main burner, said pilot burner directly heating the same thermal member to open said single one-way acting combined main gas and safety valve slightly when the pilot burner alone is operating and to completely close said single one-way acting safety valve and thereby completely cut off the flow of all gas to said main burner should the pilot burner be extinguished, said parts operating as and for the purpose described.

4. A gas burning appliance for gas ranges, comprising an oven, a manifold, a main burner in said oven connected with said manifold, a booster burner in said oven near the main burner, a fuel conduit connecting said booster burner with said manifold independent of said main burner connection with said manifold, a constantly burning pilot burner connected with said manifold inde-

pendently of said manifold connections of the main and booster burners with said manifold, a single thermal member in said oven directly heated first by gas for said constantly burning pilot and then by the gas from said booster burner, a single valve seat and a single one-way acting valve in said housing operatively connected with said thermal member for first partially opening said valve, and a manually operated valve for controlling said booster and main burner manifold connections, whereby said single one-way acting valve first partially opens by the pilot burner and then quickly fully opens by the booster burner and a single acting thermal member perform the double functions of partially and fully opening said single one-way valve as and for the purpose described.

5. A combined single safety and main burner gas control valve and a single thermal control member for gas ranges, comprising a pilot burner operating on said single thermal member to partially open said valve and to close said partially open valve should the pilot be extinguished, and a large booster burner located adjacent said thermal member and suddenly greatly increasing the expansion of the same thermal member, thereby quickly opening wide said main burner gas control valve without waiting for the sufficient heating of a cool range oven to increase the expansion of said thermal member to open wide said gas control valve.

10 6. A combined single safety and main burner gas control valve and a single thermal control member for gas ranges, comprising a pilot burner operating on said single elongated thermal member to partially open said single safety valve and an elongated booster burner located adjacent and extending parallel said single thermal member for quickly and greatly increasing the expansion of said single thermal member and quickly opening wide said main burner gas control valve without waiting for the sufficient heating of a cool range oven to increase the expansion of said thermal member to accomplish said result.

15 7. A combined safety and gas controlling means for gas ranges, comprising a housing containing a one-way acting single main burner gas control valve therein, a thermal member projecting into said housing with its inner end operatively arranged with respect to said one-way valve and its outer end arranged to be partially expanded by a pilot burner to partially open aforesaid valve, a booster burner additionally heating said thermal member and the same thermal member further and quickly expanded to quickly move said one-way valve to wide open position without waiting for the range oven to heat up sufficiently to increase the expansion of said thermal member to open wide said gas control valve.
